UNITED STATES PATENT OFFICE.

SAMUEL K. DAVIES, OF NEWPORT, KENTUCKY, ASSIGNOR TO LEE E. ACH, OF CINCINNATI, OHIO.

HAT-SHAPING MACHINE.

1,201,267.

Specification of Letters Patent. Patented Oct. 17, 1916.

Application filed October 30, 1915. Serial No. 58,801.

To all whom it may concern:

Be it known that I, SAMUEL K. DAVIES, a citizen of the United States, residing at Newport, in the county of Campbell and State of Kentucky, have invented certain new and useful Improvements in Hat-Shaping Machines, of which the following is a specification.

My present invention is an elaboration upon the invention shown, described and claimed in my application for Letters Patent of the United States, Serial No. 50,768, filed September 15, 1915.

It is the object of my present invention to provide a new and improved machine for shaping hats, especially the brims and head-size portions of the hats.

It has been the usual practice heretofore in forming the brims of women's hats to press the same between solid molds, both of which were heated, the pressure remaining upon the material until the material shall have become set to shape, the molds being separated and the formed material removed.

In the usual method thus employed the drying of the material was retarded by being inclosed between solid molds. In the usual method heretofore employed it has also been customary to provide a different set of two solid molds for each differently shaped brim and each different head-size thereof employed, making it necessary to provide a great number of coöperating pairs of solid molds for accommodating all the various shapes and head-sizes of brims.

It is the object of my invention to provide novel means whereby one of the solid coöperating molds may be dispensed with; further to provide novel means whereby the material is in view of the operator during the process of shaping; further to provide novel adjustable means whereby to impress various head-sizes by said means; further to provide an adjustable head-size coöperating part for the molds over which the materials are arranged to be stretched, so that the same coöperating head-size part may be employed for different head-sizes of different molds.

It is a further object of my invention to provide an adjustable head-size part arranged for forming either an outside head-size or an inside head-size, adjustable for either; further to provide an adjustable head-size part arranged to coact with an op-

posing mold forming a turned-down brim or with an opposing mold forming a turned-up brim; and, further, to provide novel means coöperating with the head-size parts for securing the material to the mold, so that the adjustable head-size part and said securing means may coöperate with the material for stretching the same and maintaining the same in stretched relations.

The invention will be further readily understood from the following description and claims, and from the drawings, in which latter:

Figure 1 is a front elevation of a hat shaping machine embodying my invention. Fig. 2 is a side elevation of the same. Fig. 3 is a plan view of the same. Fig. 4 is a horizontal section of the same taken on the line 4—4 of Fig. 2. Fig. 5 is a central vertical section of the material forming parts, taken on the line 5—5 of Fig. 4, and showing the same applied for forming a hat-brim with an outside head-size part. Fig. 6 is a similar view, showing parts as forming a hat-brim with an inside head-size part. Fig. 7 is a bottom view of the flexible band and its adjusting means. Fig. 8 is a detail of the same taken on the line 8—8 of Fig. 7. Fig. 9 is a cross-sectional detail of the same taken on the line 9—9 of Fig. 7. Fig. 10 is a perspective view of a portion of the flexible band showing the clips applied thereto. Fig. 11 is a detail view in section, taken on the line 11—11 of Fig. 1. Fig. 12 is a detail view in section, taken on the line 12—12 of Fig. 11. Fig. 13 is a detail view of one of the arms for the flexible tension-member, partly in section on the line 13—13 of Fig. 4. Fig. 14 is a detail of the eccentric link-connection for the slide-frame, partly in section taken on the line 14—14 of Fig. 1; and, Fig. 15 is a cross-sectional detail on the line 15—15 of Fig. 2.

21 represents the main frame of the machine, with relation to which a slide-frame 100 22 is movable. In the present exemplification the slide-frame comprises upright rods 23, connected at their upper ends by a cross-piece 24 and at their lower ends by a cross-girt 25, the rods sliding in bearings 26 in the main frame. The cross-piece 24 was arranged in machines as heretofore employed, to have an upper solid mold coacting with the lower mold herein shown, suspended therefrom by suitable clamps in slots 27. 110

5 A head 30, shown in the form of a plate or spider, is located at the top portion of the slide-frame and is adjustable thereon by means of nuts 31, 32, adjustable lengthwise of the threaded ends 33 of the rods 23, for adjusting the head and cross-piece lengthwise of said rods and clamping said head in adjusted positions.

10 The main frame is provided with a table 35, having a pedestal 38 secured thereto, a lower mold being clamped to the pedestal by means of hook-clamps 40. The lower mold may be of suitable shape or size and preferably is a mold for forming a hat-brim thereover having a head-size. Such a lower mold for forming a brim with an outside head-size is exemplified at 41 and such a mold exemplified as forming a brim with an inside head-size is exemplified at 42. 15 These molds may be of any desired shape or size depending on the shape or size it is desired to give the brim or the head-size of the hat. 20

The mold 41 is represented as having a 25 protruding part 43 for forming an outside head-size part, and the mold 42 is represented as having a hollow 44, the peripheral wall of which forms an inside head-size part.

30 I provide an adjustable part coöperating with the head-size part, and exemplified for coöperating with either the inside head-size part or the outside head-size part, for shaping the head-size parts of the hat. I have 35 exemplified this adjustable part as formed by a flexible band 51. This flexible band may be composed of metal, preferably a spring metal, as spring steel. The flexible spring band forms an adjustable coöperating part for the mold. It is arranged to have lapping ends 52, 53, forming preferably a closed path, the laps being adjustable for adjusting the size of the closed path, for accommodating for instance different sizes of head-size parts of the molds. 40

45 For adjusting and holding the head-size part in position and for moving the same into coacting relation with the material, I have exemplified the following instruments: A support 55 depends from the head 30, preferably by means of rods 56 having connection, exemplified as a threaded connection 57 in Fig. 8, with the support, and adjustable up and down on the head by 50 means of nuts 58, 59, the rods 56 being received through slots 60 in the head. Blocks 61 are adjustable toward and from each other on the support, preferably lengthwise of slots 62 in the support, being clamped in 55 adjusted positions by means of clamp-nuts 63. The blocks 61 are adjustable for determining the position and adjustment of the flexible band 51. Slides 64 have rollers 65 journaled thereon and are adjusted lengthwise of the slots 62 by means of screw-rods

66 turned by means of hand-wheels 67, the screw-rods being journaled in bearings 68, 69, in the support 55. The screw-rods pass loosely through holes 70 in the blocks 61. The turning of the screw-rods will move the 70 rollers 65 toward and from the blocks 61 for clamping the flexible band 51 between said rollers and blocks, or for releasing said flexible band. The lapping ends of the flexible band preferably pass two of the 75 blocks and rollers for preventing torsional movement of the band and maintaining the band in adjusted position.

The extreme ends of the band may, if desired, be held toward the body of the band 80 by means of clips 71 which are preferably spring-clips for pressing said ends toward the body of the band and forming a continuous edge along the edge of the band for contacting the material, for aiding which 85 purpose the ends of the band may be tapered, as shown at 72.

The flexible band may be adjusted so as to be received outside the material 73 stretched about the protruding part 43 of 90 a mold, forming an outside head-size, or within the material 74 stretched across the peripheral wall of the hollow 44, for forming an inside head-size, the adjustments of the band permitting its adjustments to minutest degree for forming either inside head-sizes or outside head-sizes of various head-sizes that may be employed. The supporting and adjusting means are so arranged that the forming end of the flexible band extends beyond the supporting and adjusting means for being readily received past the mold parts controlling the shaping of the hat. 100

By means of the adjusting means an 105 ellipse, round or other cross sectional form of head-size may be provided, determined by the relative adjustments of the blocks 61 and the coöperative clamping of the rollers 65.

I have shown, described and claimed 110 means in my aforesaid application for holding the outer edge of the material of the hat-brim in place during shaping of the same, and while these parts are herein shown and described, they are not claimed 115 herein in so far as the same are claimed in my aforesaid application. These parts may be briefly described as follows: A flexible tension-member 75 is arranged to be received about the material and the edge of the hat-brim mold. This tension-member may be instanced as a wire cable. It is arranged to be placed in position about the mold, and when in such position, to be drawn taut against the material which has been stretched about the mold for holding the material in stretched relation. The mold may be a cold mold, the material arranged to be pasted to the mold for shaping the same, as in hand-made hats, but usually the mold is 120 125 130

arranged to be heated, as by gas through the medium of gas-jets supplied from suitable openings in a ring-pipe 76, fed by a pipe 77 leading to a suitable point and provided with a valve 78.

5 In the present exemplification the tension-member is arranged to be received in clips 81, shown as spring clips, secured to the free ends of rods 82 by means of screws 83. 10 The rods 82 are spring-rods, adjusted to positions laterally, so as to normally hold the tension-member somewhat distanced from the peripheral edge of the brim-portion of the mold. These rods pass through 15 the slots 27 and are arranged to be adjusted laterally in the slots 60 and to be adjusted up and down and secured in adjusted positions in the slots by means of the nuts 84. 20 85. The closed path of the tension-member is exemplified at 88, from which stretches 89 extend in opposite directions toward the sides of the machine, the respective ends of the closed stretch crossing each other in the forward clip, as exemplified in Figs. 1 and 25 4. The tension-member is drawn taut about the mold by suitable means, exemplified as extensions of said tension-member, it being understood that the term "flexible tension-member", wherever employed does not 30 include the drawing or pulling means.

The extensions of the tension-member are exemplified as the stretches 89, continued over pulleys 90 as stretches 91, which are continued over pulleys 92 as stretches 93, 35 85 which are continued over pulleys 94, as stretches 95 received about a pulley 96, acting as an equalizer pulley, and arranged to be pulled upon for applying tension to the tension-member.

40 In my improved device motion is imparted between the mold and the flexible band and tension-member, so as to cause coactive positioning between said flexible band and tension-member and the mold, accomplished in 45 the present exemplification by depressing the flexible band and tension-member.

The material to be stretched may be of any desired fabric, for instance buckram, velvet or other fabric, to form the hat-brim. 50 The material is usually dampened prior to being shaped. A usual material employed is buckramette, which has been provided with a stiffening substance and dampened and having a piece of velvet or other material undampened laid over one or both sides of the same with its nap exposed, the superposed materials being placed upon the mold and then pulled over the mold by the operator, two operators usually serving a 55 machine, and both operators taking the superposed material by means of the hands and pulling the same over the mold. The space occupied by the tension-member is comparatively small and does not interfere 60 with the hands of the operator, waste of 65

material being thereby avoided in my improved device.

For depressing the sliding frame having the head-size band and flexible tension-member thereon, I exemplify a treadle 101 pivoted on a tie-rod 102 between the side frame of the main frame. A link 103 is articulated with the treadle by a pin 104 and has a bearing 105 about an eccentric 106 on a rock-shaft 107, journaled in bearings 108, 109, in the slide-frame and having an operating arm 110 secured thereto. Depressing the treadle will depress the slide-frame, the treadle being arranged to be received under a catch 111 for holding the 80 same in depressed position.

The object of depressing the slide-frame is to bring the head-size band and the flexible tension-member into cooperative position or approximately so with the material 85 on the lower mold. If desired, the eccentric connection 106 may be dispensed with, and the link 103 articulated directly with the slide-frame, for bringing the parts into co-operative relation, but I prefer to bring the 90 parts into approximate co-operative positions by means of the treadle and to complete the co-operative relation by means of the operating arm 110 for rocking the eccentric and depressing the slide-frame to final 95 position.

Thus the material is positioned in partly stretched relation over the mold and the slide-frame depressed by means of the treadle, whereby the head-size band depresses 100 the material part-way upon the mold. The material is then stretched to full extent over the mold and the depression of the slide-frame completed by operation of the operating arm 110, for rocking the eccentric, and 105 thereby drawing the head-size band toward the mold and completing the stretching of the head-size portion of the material, it being understood that meanwhile the outer edges of the material are being held in 110 stretched relation by the operators. The flexible tension-member is then drawn taut about the outer edge of the mold, representing the outer edge of the hat-brim, which is accomplished by means of a treadle 115, pivoted about the pin 104, a link 116 being articulated to the treadle at 117 and to the casting of the pulley 96 at 118. The treadle is held in depressed position by means of any one of a series of teeth 124 of a catch 125. 115

The link 116 is preferably adjustable for adjusting its length for accommodating adjustments of the rods 82 to accommodate various molds, this adjustment being accomplished by making the link a two-part link, 120 the link-parts passing through holes 119 in clamp-blocks 120, in which they are clamped in adjusted positions by set-bolts 121.

In order that the flexible tension-member may have a secure grip upon the edge of the 130

material, I provide the mold with a peripheral groove 122 into which the flexible tension-member presses the material for maintaining the material in stretched relation. 5 For normally causing rising movement of the slide-frame I provide a lever 126 pivoted on a cross-rod 127 and having a weight 128 thereon. A link 129 is articulated at 130 with the lever and at 131 with the link 10 103. Means are provided for adjusting the positions of the pulleys 90 in accordance with the adjusted position of the forward one of the rods 82, so that the stretches 89 may pass from the closed stretch of the 15 flexible tension-member without undue deflecting strain upon said rod. Thus the pulleys 90 are shown journaled on shoulder-bolts 135 received through pulley-housings 136. Each of the pulley-housings is arranged to slide in a guideway 137, a clamp-nut 138 fixing the parts in adjusted positions. The guideway 137 is in a guide-piece 139, adjustable forward and back on a guide 140, and arranged to be clamped in adjusted 20 positions by means of bolts 141 passing through apertures in said guide and through a slot 142 in said guide-piece and threaded into a clamp-plate 143. The guides 140 are respectively clamped to the upright rods 23 25 by means of clamp-bearings 145, a tie-rod 146 connecting the rear ends of the guides 140 at the respective sides of the machine. The pulleys 92 and 94 are arranged to move with the slide-frame, being pivoted on a cross-bar 151 fixed in bearings 152 of hangers 153, respectively clamped to the upright rods 23 by means of clamp-bearings 154.

When the material has been stretched about the mold with the head-size band 40 and flexible tension-member in operative relation for maintaining the material in stretched relation, the material is allowed to remain thus stretched about the mold until the same has become fixed to shape, the 45 time for accomplishing which is materially reduced in my improved device, for the reason that the material is exposed to the atmosphere, permitting the ready evaporation of steam, if a heated mold is employed, and 50 consequent drying of the material. When the material has become sufficiently dry, the flexible tension-member is released, and the slide-frame raised for releasing the material, which is then removed from the mold.

55 In my improved device the material may be locally rearranged after engagement of the flexible tension-member with the material for local stretching or rearrangement of the material, at points about the hat-brim, 60 so as to insure any degree of stretching at the edge of said brim or in adjacency to the adjustable head-size band, or to control the shape of the stretching, as may be desired, the operator having the whole of the material in full view.

My improved device is so arranged that the flexible head-size band and its supporting and adjusting parts and the flexible tension-member and its supporting and operating parts may be attached to any of the 70 well-known designs of stamper hat presses to which they may be adapted, replacing the upper solid mold of the same and avoiding the disadvantages of the upper, solid mold, the saving of the gas consumption necessary 75 to heat said upper mold when heated molds are employed, and providing a better finished article.

Having thus fully described my invention, what I claim as new and desire to secure by 80 Letters Patent, is:

1. In a hat shaping machine, the combination of a mold comprising a head-size part, a flexible band, means for adjusting said flexible band into shape to coöperate with said head-size part, and means causing approach and recession between said flexible band and said mold axially of said mold during operation of the machine. 85

2. In a hat shaping machine, the combination of a mold comprising a head-size part, a flexible band, means for adjusting said band into shape and size for coöperation of its edge with said head-size part, and means for approach and recession between said flexible 95 band and said mold axially of said mold during operation of the machine for co-operation of said edge with said head-size part. 90

3. In a hat shaping machine, the combination of a hat-brim mold comprising a head-size part, a flexible band directed edgewise toward said mold, means for adjusting said flexible band to shape and size for coöperation of its edge with said head-size part, a 105 flexible tension-member, means for positioning said flexible tension-member outside the longitudinal projection of the periphery of the brim-portion of said mold, means for approach and recession between said band and tension-member and said mold, and means for drawing said flexible tension-member taut about said brim-portion of said mold. 110

4. In a hat shaping machine, the combination of a hat-brim mold comprising a head-size part, a flexible band directed edgewise toward said mold, means for adjusting said flexible band to shape and size for coöperation of its edge with said head-size part, a 115 flexible tension-member, means for positioning said flexible tension-member outside the longitudinal projection of the periphery of the brim-portion of said mold, means for stepwise approach and for recession between said band and tension-member and said mold, said stepwise approach bringing said band and tension-member and said mold consecutively stepwise into approximate co-operation and ultimate coöperation, and 120 125 130

means for drawing said flexible tension-member taut about said brim-portion of said mold.

5. In a hat shaping machine, the combination of a hat-brim mold provided with a peripheral groove, a flexible tension-member, means for resiliently positioning said flexible tension-member outside the longitudinal projection of the periphery of said mold, 10 means for causing approach and recession between said flexible tension-member and said mold axially of said mold during operation of the machine, and means for drawing said flexible tension-member taut about 15 said mold for squeezing the material being shaped into said peripheral groove by means of said flexible tension-member.

6. In a hat shaping machine, the combination of a mold-support, a flexible head-size band having its edge presented toward 20 said mold-support, a support for said band, slides on said band-support, means for locating said slides in relatively adjusted positions on said band-support, and means for 25 clamping said flexible head-size band to said slides whereby to adjust the size and shape of the inclosed space within said flexible head-size band.

7. In a hat shaping machine, the combination of a mold-support, a flexible head-size band having its edge presented toward 30 said mold-support with its ends inlapping relation, a support for said band, slides on said band-support, means for locating said 35 slides in relatively adjusted positions on said band-support, means for clamping said flexible head-size band to said slides, a clip received over an end and the body of said flexible head-size band, and means for causing 40 coöperative movement between said supports.

8. In a hat shaping machine, the combination of a mold-support, a flexible band having its edge presented toward said mold-support, a support for said band, slides on 45 said band-support, means for locating said slides in relatively adjusted positions on said band-support with said band lapping across a plurality of said slides, means for 50 clamping said flexible head-size band to said slides whereby said band is clamped at a plurality of points in lapping relations, and means for causing coöperative movement between said supports.

55 9. In a hat shaping machine, the combination of a mold-support, a flexible band having its edge presented toward said mold-support, a support for said band, slides on 60 said band-support, slots in said band-support along which said slides are adjusted, means for clamping said slides in adjusted positions, coöperating slides for said first-

named slides, screw-rods having operative connections with said second-named slides for clamping said flexible band between said 65 coöperating slides, and means for causing coöperative movement between said supports.

10. In a hat shaping machine, the combination of a mold-support, a flexible band 70 having its edge presented toward said mold-support, a support for said band, slides on said band-support, slots in said band-support along which said slides are adjusted, means for clamping said slides in adjusted 75 positions, coöperating slides for said first-named slides, screw-rods journaled in said band-support passing through said first-named slides and having threaded connections with said second-named slides for 80 clamping said flexible band between said slides, and means for causing coöperative movement between said supports.

11. In a hat shaping machine, the combination of a mold-support arranged to support a mold, a slide-frame, a band-support, a flexible band depending from said band-support in a closed path with its edge presented toward said mold, means on said band-support for adjusting the size of the 90 closed path of said band, rods depending from said slide-frame outside said band-support and said adjusting means thereon, a flexible tension-member supported by said rods in a closed path of greater size than 95 the size of the closed path of said flexible band, means for moving said slide-frame whereby said band-support and flexible tension-member are moved toward said mold, and means for drawing said flexible tension-member taut about said mold. 100

12. In a hat shaping machine, the combination of a main frame, a lower mold-support, a mold thereon, a slide-frame slidable on said main frame, a flexible band forming 105 a closed path directed edgewise toward said mold-support, a support for said band, means on said support for adjusting the size of the closed path of said band, a flexible tension-member, means for supporting said 110 flexible tension-member from said head, means for adjusting said last-named supporting means and said band-support relatively one to the other toward and from said mold-support, means for drawing said flexible tension-member taut about said mold, and means for moving said slide-frame. 115

In testimony whereof, I have hereunto signed my name in the presence of two subscribing witnesses.

SAMUEL K. DAVIES.
